Inventor:

Herrman Bruckerman

UNITED STATES PATENT OFFICE.

HERMAN BRUCKERMAN, OF TABLE ROCK, ASSIGNOR OF ONE HALF TO FREDERICK BRUCKERMAN, OF POKER FLAT, CALIFORNIA.

CAN-OPENER.

SPECIFICATION forming part of Letters Patent No. 376,577, dated January 17, 1888.

Application filed October 25, 1886. Serial No. 217,173. (No model.)

To all whom it may concern:

Be it known that I, HERMAN BRUCKERMAN, of Table Rock, in the county of Sierra and State of California, have invented certain new and useful Improvements in Can-Openers; and I do hereby declare the following to be a full, clear, and exact description of the invention, such as will enable others skilled in the art to which it pertains to make and use it, reference being had to the accompanying drawing, which forms part of this specification.

My invention relates to an improvement in can-openers; and it consists in a suitably-shaped blade provided with a handle and having a bend at nearly right angles at its inner end, and a suitable notch formed in the bend, as will be more fully described hereinafter.

The object of my invention is to provide a can-opener which is so shaped that with it persons can open tin cans of all shapes with ease and without any danger of cutting themselves.

The accompanying drawing is a perspective view of a can-opener embodying my invention. 25 H represents the handle, and I the steel shank which is inserted therein. Upon the outer end of this shank is formed the sharp-pointed blade C, which may be either of the shape here shown or any other that may be 30 preferred. At the inner end of this blade C the shank is given a bend, D, at or about right

angles, and in this bend is formed a sharp-edged notch, A, in order to catch over the edge of the can that is being opened after the blade C has been forced down through its top 35 and the handle turned down, as shown in dotted lines, and thus form a fulcrum upon which the handle turns. The edge of this notch A is made sharp, so that when the handle is turned down this sharp edge makes a slight indentation on the rim of the can and acts as a catch or ratchet, and thus while acting as a fulcrum for the handle will prevent the blade from slipping back. Whether a round or a square can 40 is being opened, the notch catches over the edge of the can and forms a fulcrum upon which the handle is pressed downward, while the blade is forced upward to cut through the top of the can.

Having thus described my invention, I claim—

A can-opener consisting of the shank I, provided with the bend D, having the notch A in one edge, and the blade C, bent substantially parallel with said shank, substantially as shown and described.

In testimony whereof I affix my signature in presence of two witnesses.

HERMAN BRUCKERMAN.
